Primary Examiner — John R Yeh(74) *Attorney, Agent, or Firm* — Daniel M. Cohn; Howard M. Cohn(57) **CLAIM**

The ornamental design for a car wash mop as shown and described.

DESCRIPTION

FIG. 1 is a perspective view of a car wash mop showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is an enlarged top plan view thereof;

FIG. 8 is an enlarged bottom plan view thereof;

FIG. 9 is a partial enlarged view of portion 9 in FIG. 1;

FIG. 10 is a partial enlarged view of portion 10 in FIG. 1;

FIG. 11 is a partial enlarged view of portion 11 in FIG. 2; and,

FIG. 12 is a partial enlarged view of portion 12 in FIG. 2. The even-dashed broken lines depict portions of the car wash mop that form no part of the claimed design. The dot-dash broken lines depict enlargement indications and form no part of the claimed design.
